N. N. S. DAUDELIN.
SEPARATING DEVICE.
APPLICATION FILED JAN. 2, 1913.

1,074,931.

Patented Oct. 7, 1913.

UNITED STATES PATENT OFFICE.

NARCISSE N. S. DAUDELIN, OF FALL RIVER, MASSACHUSETTS.

SEPARATING DEVICE.

1,074,931.

Specification of Letters Patent.

Patented Oct. 7, 1913.

Application filed January 2, 1913. Serial No. 739,681.

To all whom it may concern:

Be it known that I, NARCISSE N. S. DAUDELIN, a citizen of the United States, residing at Fall River, in the county of Bristol and State of Massachusetts, have invented certain new and useful Improvements in Separating Devices, of which the following is a specification.

My invention relates to separating devices for use upon spinning frames, twisters, or any other machines upon which a separating device is of use, and has for its essential objects the prevention of the breakage of thread or yarn due to the ballooning of the same. At present the location of the separator plate, and its want of suitable adjustability, has contributed to yarn breakage.

A further object is to provide a structure which will not injure the fingers of the operator and which is accessible to apply, remove or adjust.

Another object is to enable the use of ring travelers of less weight than heretofore.

Further objects are to secure the recited ends in a structure which is simple, of few parts and easy to apply.

Other objects will be referred to in the following specification.

To the above ends referred to my invention consists in such parts and such combinations of parts as fall within the scope of the appended claims.

In the accompanying drawings which form a part of this specification:—Figure 1 is a side elevation of my device applied to the adjacent portion of a spinning frame, Fig. 2 a rear elevation of the same, and Fig. 3, a plan of the same.

Like reference characters indicate like parts throughout the views.

In the drawings 1 is the spindle rail, 2 the ring rail and 3 the spindle of an ordinary spinning frame, the other well known parts being omitted as being understood in the art.

My device or attachment comprises a plate or block 6 having a rounded upper rear portion 7 and an arm 8 extending forwardly from its lower portion, together with a second arm 9 extending parallel with the arm 8 from the upper portion of the member 6, the arm 9 being provided with a longitudinal slot 10. Passing through the slot 10 is a binding screw 11 engaging a threaded opening 12 in the ring rail and provided with a head 13 overlapping the upper face

of the arm 9. The arms 8 and 9 slidably embrace the rear margin of the rail 2. By virtue of the screw 11 the member 6 can be adjusted transversely of the rail 2 into such position as the particular work upon the machine may require. A separator bar 15 extends longitudinally of the frame 17 of the machine and rests in a flat recess 18 in a plate 19 forming longitudinal ribs 20 along the side faces of the bar. An arm or ear 21, integral with the plate 19, extends at right angles to the latter and is provided with an opening 22 substantially circular in outline but provided with a cavity 23 at its lowest portion. In the side of the member 6 is a cylindrical stud or projection 25 extending loosely through the opening 22 and provided near its extreme end, exterior of the ear 21, with a lug or ear 26 of sufficient magnitude to permit its insertion through the cavity 23, but normally out of alignment with the cavity 23 and disposed at an angle to the latter, whereby the member 19, 21 may swing upon its pivot member 25 without danger of disengagement from its pivot member. It will be understood that there are a plurality of plates and arms 19, 25 located at intervals along the separator bar 15 and at its ends. The bar 15 is attached to the arms 19, 21 by means of screws 27 passing through oblong openings 28 in the bar and registering in threaded openings 29 in the members 19, and provided with heads 30.

Mounted at intervals upon the bar 15 are separator blades 32 provided with flat bodies 33 having a plurality of openings therethrough 34, which body is connected by a downwardly directed integral neck or arm 35 to a horizontal plate or bearing portion 36 provided upon its under face with a transverse rectangular channel 37 forming interspaced transverse shoulders or flanges 38, whereby the bar 15 upon which the plate 36 is mounted maintains the blade 32 in rigid and unvarying position at right angles to the bar 15. The plate 36 is perforated as 40 to admit passage therethrough of either the binding screw 27, already described, or a similar screw 41 in the bar 15 provided with a head 42 of greater diameter than the perforation 40. Under the screw heads 30 and 42 may be placed washers 43. Obviously the screws 41 are employed upon a majority of the separator blades, since in the other

instance the screws 27 serve not only the function of retaining the separator blades, but also of holding the bracket plates 19, 21.

In operating the above device, when it is desired to doff the spindles the separators, the separator bar, and the brackets 19, 21 are thrown back into the position shown in broken lines in Fig. 1, where the parts are restrained against excessive downward movement, or are stopped, by the frictional engagement of the underface of the plate 19 with the curved rear face of the member 6, since the length of the lower portion of the member 6 at its lowest point exceeds the length of the inner face of the arm 21. The normal position of the parts during the operation of the machine to which my device is attached is shown in full lines in Fig. 1. Herein it will be observed that my device being located upon the ring rail, and upon the rear edge of the same, is not only conveniently located with regard to the work to be performed, but is in a constant relation to the traveler 45 of the ring 46. In this position separator blades are always in a constant and proper and most advantageous position to contact with the balloon, regardless of whether the ring rail is moving upwardly or downwardly. This result can not be obtained when the separator blades are located upon any portion of the machine frame which bears a fixed relation relatively to the motion of the ring rail. The particular formation of the plates 32, and their supporting portions 36, make it possible to impart to the plates a maximum of strength with their points of connection with the bar 15, because excessive angular bending is not required. This construction of blade also locates the head of the attaching screw in an accessible position to the operator when it is desired to remove the screw. The perforations 34 in the blades prevent the "dragging" of the thread or yarn, that is, these holes serve to break the vacuum or furnish a circulation of the air that prevents engagement of the balloon with the blade itself.

By virtue of the slots 10 and 28 it will be noted that the blades 32 are adjustable both transversely to the ring rail, and longitudinally thereof, whereby the separators may be arranged as necessitated by the particular class of work sought to be done upon the machine at different times.

What I claim is:—

1. In a separating device, the combination with the ring rail, of blocks comprising curved rear end portions, and interspaced forwardly extending arms embracing the ring rail, one of said arms being provided with an oblong slot, screws in the ring rail passing through said slots, heads upon the screws of greater diameter than the breadth of the slots, studs upon the bodies of the blocks, brackets comprising horizontal plates, and arms disposed at right angles to the plates provided with openings to loosely receive the studs, a separator bar upon the horizontal portion of the bracket provided with a longitudinal opening, and a screw in the horizontal portion of the bracket passing through the opening, a head upon the screw of greater diameter than the width of the opening, and separator blades fixed to the bar. 75

2. In a separating device, the combination with the ring rail, of blocks fixed to the rear portion of the ring rail and provided with curved rear end portions gradually increasing in radii toward the bottoms of the blocks to form a stop for the downward travel of the separator bar, studs upon the sides of the blocks, brackets comprising horizontal portions, and downwardly directed arms integral with the horizontal portions, said arms being of less length than the length of the greater radii of the curved portions of the blocks, a separator bar fixed to the brackets, and separator blades fixed to the bar. 80

3. In a separating device, the combination with a ring rail, of blocks fixed to the rear of the ring rail, studs upon the sides of the blocks, lateral lugs upon the ends of the studs, brackets comprising horizontal plates and integral downwardly extending arms, each arm being provided with an opening through which passes the stud, and provided with a cavity extending from said opening, a separator bar fixed to the horizontal portions of the brackets, and separator blades mounted upon the bar. 85 100

In testimony whereof I have affixed my signature in presence of two witnesses.

NARCISSE N. S. DAUDELIN.
